UNITED STATES PATENT OFFICE.

G. D. WEST, OF BRANDYWINE, DELAWARE, ASSIGNOR TO P. W. NEEFUS, OF NEW YORK, N. Y.

VALVE-MOTION OF OSCILLATING STEAM-ENGINES.

Specification of Letters Patent No. 23,519, dated April 5, 1859.

To all whom it may concern:

Be it known that I, GEORGE D. WEST, of Brandywine Hundred, Newcastle county, State of Delaware, have invented a new 5 Valve-Motion for Oscillating Engines; and I do hereby declare that the following is a full and exact description thereof, reference being had to the accompanying drawings and to the letters of reference marked 10 thereon.

The drawings represent elevations of an oscillating cylinder and its crank in different positions.

Figure 1, shows the cylinder and crank 15 at the center and my improved attachment in such a position, as to give no motion to the valves. Fig. 2 represents cylinder and crank in two positions, and my attachment in such a position, as to give the crank a 20 motion in direction of the arrow. Fig. 3, shows the engine with an attachment for a lead to the valves, and my valve motion in a position to give the crank a reversed motion. Fig. 4, is a detached view of rock 25 shaft and its crankarms. In all these figures the frame of the engine is omitted.

The nature of my invention consists in providing an arch and an intermediate lever, to produce a quick and sudden motion 30 in the valves of the oscillating engine.

To enable others skilled in the art to make and use my invention I will proceed to describe its construction and operation.

A represents an oscillating cylinder with 35 its center of vibration at a'.

b b are the valves. The stem of these valves is hinged to the upper end of a lever c on the side of the cylinder a which lever c turns on a stud c' fixed to cylinder a. The 40 lower end of this lever c extends downward

below the fulcrum c' to the center line of the cylinder a, where it enters with a pin the slot of an arch d. This arch d turns on a fulcrum d', and is made concentral with the center of vibration of cylinder a unless it is placed eccentric by lever e and connecting rod f. If arch d is placed in a concentral position with a' by lever e as shown in Fig. 1, it is evident, it will impart no motion to the valves b and consequently the engine will stop. But if arch d is placed in an eccentric position by means of lever e the engine will turn in direction of arrow, and the position of cylinder a shown in red lines in the same figure illustrates how fast the 45 opening of the ports take place as the crank has traveled a short distance only. If no lead were required it would be sufficient to give arch d a stationary fulcrum at d' in the frame of the engine, but in order to give 50 the valves a lead I propose to apply the well known device of 2 eccentrics and an arch as shown in Fig. 3, and connect this arrangement with arch d, by a rock-shaft g which has its bearing in some convenient 55 part of the frame and contains a crank arm h and i on each end. To the upper end of arm h I attach the fulcrum of arch d and the upper end of arm i is provided with a pin k, which enters the slot of arch l. 60

Having thus fully described my invention what I claim therein and desire to secure by Letters Patent is—

The combination of arch d and lever e for the purpose and in the manner substantially as set forth. 75

GEORGE D. WEST.
